(57) **CLAIM**

The ornamental design for speaker covers of headphones as shown and described.

DESCRIPTION

FIG. 1 is a right perspective view of speaker covers of headphones showing our new design, under a first embodiment;

FIG. 2 is a left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a right perspective view of speaker covers of headphones showing our new design, under a second embodiment;

FIG. 10 is a left perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The shade lines in the Figures show contour and not surface ornamentation. The short dash broken lines in the Figures form no part of the claimed design.

1 Claim, 16 Drawing Sheets
